UNITED STATES PATENT OFFICE.

WALDO SHELDON, OF SOUTH NORWALK, CONNECTICUT.

WELL-DRILLING APPARATUS.

Application filed March 4, 1926. Serial No. 92,126.

The present invention relates particularly, though not exclusively, to well drilling apparatus of the type such as disclosed in my co-pending application, Serial Number 6,535, 5 wherein the feed of the drill is governed by power mechanism which is operative independently of the rotary action of the table.

Special objects of the invention are to provide practical and efficient means for 10 gripping the drill pipe and for imparting the rotation of the table thereto; to provide such gripping means in a relatively simple structure and in such form that it may be quickly and easily set up and also be 15 readily releasable; to unify the grip and the clamp means by which the same is held so that there is but one set of parts to be handled and to provide simple and efficient means for automatically "breaking" the hold 20 on the pipe when the clamping means for the grip is released.

Other objects and the various novel features of construction, combination and relation of parts by which all are attained will 25 be clear from the following specification which includes the accompanying drawings illustrating different practical embodiments of the invention.

Figure 1 is a vertical sectional view of a 30 form of the invention in which the grip and the overstanding clamp are connected integrally and are shown mounted in a power actuated drive sleeve slidingly keyed in the rotary table. This view is taken as on line 35 1-1 of Figure 4.

Figure 2 is a detached view of another form of grip made in segments loosely connected with the overstanding clamp bar.

Figure 3 is a partial plan view of the 40 same.

Figure 4 is a top plan view of the structure shown in Figure 1.

Figure 5 is a bottom plan view of one of the unitary grip and clamp bar sections.

In Figure 1 a portion of the rotary table 45 is indicated at 7, the same being shown as having a cylindrical passage 8 therethrough for the drive sleeve 9, which latter is slid- 50 ingly held in said passage by keys 10 fast in the table and engaging keyways 11 in the sleeve. In this fashion the drive sleeve is caused to rotate with the table but is free to be raised and lowered by the power mechanism.

55 Only part of the power mechanism is

shown, the hollow piston rod 12 slidably held to the inner annular cylinder wall 13 by keys 14, said piston rod carrying at its upper end, a conical roller bearing 15, supporting the head of the drive sleeve. A 60 similar bearing, not shown, at the bottom enables the piston rod to transmit downward pressure to the drive sleeve. Thus, by proper control of the power cylinder, power may be applied for lifting or for feeding 65 the drill stem held in the drive sleeve.

The gripping means for holding and imparting the rotation of the table to the drill pipe comprises in Figures 1, 4 and 5, a collet structure made up of two substantially 70 semi-circular collet sections 16, 17, having serrated or toothed inner surfaces 18 for gripping the pipe 19 and downwardly tapered outer surfaces 20 seating in a conical socket 21 in a bushing 22 fixed in an 75 adapter 23 which is secured as by bolts 24 fast in the head of the drive sleeve.

The pipe gripping collet sections 16, 17 are forced down into the socket provided therefor and hence into holding engagement 80 with the pipe by overstanding clamp means consisting of the bars or plates 25, 26 acted upon by the bolts 27, 28.

An important novel feature of the present 85 invention is that the drive grip and the clamp for the same are combined as a unitary structure. In the first form of the invention this is effected by connecting the clamp and collet sections integrally by means of a unitary neck portion 29.

The connection between the grip and clamp need not, however, be an integral or solid connection. Thus, as shown in Figures 2 and 3, the grip may have a loose connection with the clamp. In the structure illustrated the grip is made up of six arcuate sections, three of which are shown in Figure 2 at 30, 31, 32, connected to one of the clamp plates 33 by having angular head portions 34 engaged loosely in correspondingly shaped but larger seats 35 provided in the under side of the plate, being held therein by the bolts 36. These bolts are shown as having their heads received in cavities 37 in the top of the plate and as having their shanks extending loosely down through openings 38 into the heads 34, the under sides of the bolt heads being rounded at 39 to enable the bolts to rock 100 freely and slide one way or another to per-

mit the segments to accommodate themselves individually to a proper seat in the socket and a proper gripping engagement with the pipe.

5 In both forms of the invention illustrated, therefore, each half of the drive grip, whether it be solid or segmented, is carried by an overstanding clamp bar and so may be handled and manipulated as a unitary 10 part of the clamp bar. In the integral form, the grip sections may be slotted as indicated at 40 to provide independently yieldable segments (see Figure 5) but somewhat greater freedom of self-adjustment is allowed for 15 in a structure such as shown in Figure 2 where the grip segments are formed independently and are loosely connected with the clamp bar.

The form of the holding serrations or 20 teeth may vary to suit different conditions, but it has been found that the making of the teeth on the lines of coarsely pitched screw threads such as indicated at 41 in Figure 1 is highly advantageous because in 25 the event of any slippage on the pipe, the tendency of these inclined teeth is to screw themselves down over the pipe and hence force the grip deeper into its socket.

To enable the clamp bolts to act on both 30 clamp plates simultaneously, the ends of such plates are brought together in overlapping relation beneath the heads of the bolts by providing in the present instance, overlapping portions 42, 43 at the opposite ends of 35 the two plates, said overlapping portions having the reversely facing transverse open slots 44, 45 respectively to engage over the shanks of the bolts from opposite sides. This structure enables the clamp bars with 40 the attached grip sections being engaged laterally from opposite sides about the pipe and as the grip members drop into the socket, the slotted ends of the clamp bars naturally fall into overlapped relation en- 45 gaged beneath the heads of the clamp bolts. Because of such overlapped relation, the setting up of these bolts automatically seats both grip sections so that the grip is interlocked with the pipe by simply tightening 50 the two bolts. Conversely, the loosening of only these two bolts serves to release the grip from the drill pipe.

Special provision is made in the present disclosure for automatically lifting the clamp 55 and grip structure by the simple operation of unscrewing the clamp bolt. For this purpose these bolts are shown as having annular shoulders 46, Figure 1, spaced clear of the table top or drive sleeve and also clear of the 60 lower clamp plate. When the bolts are backed up it will be seen that these shoulders 46 will pick up the lower clamp plate at 47 and thereby lift the plates with their attached drive grips. This lifting action automatically releases the grips from their hold-

ing engagement with the drill pipe, the screw bolts providing a simple and positive means by which this result can be quickly and easily effected.

An additional releasing effect is attained 70 in the structure disclosed in Figure 1 by locating separating studs 48 between the clamp bars, said studs having downwardly faced beveled heads 49 positioned to engage correspondingly beveled inclines 50, 51 on 75 the opposing edges of the two clamp bars. It will be seen that the lifting movement of the clamp bars will bring the opposing inclines 50, 51 into engagement with the beveled heads of the studs 48 and that these will 80 thereupon operate as wedges to positively force the clamp bars and grips apart. The combined effect of the clamp bolts and separating wedges, when the bolts are turned upwardly, is thus both to lift and to positively open up the clamp and grip mechanism. The release of the grips from the drill pipe is thus accomplished simply and positively with but slight exertion and in quick order. The clamp bolts are shown made quite heavy 85 so as to be fully capable of carrying the rotation of the table to the drill pipe driving grips.

What is claimed is:

1. In well drilling apparatus, the combination with a rotary table and a tapered socket partaking of the rotary movement of the table, of a sectional clamp overstanding said socket and comprising separable clamp plates independently engageable about the 100 sides of the drill pipe extending down through the table, drill pipe gripping segments dependent from the sections of said overstanding clamp, said clamp sections having a bearing on the heads of said segments 105 and means for forcing the sections of the clamps downwardly with respect to the table to thereby force the pipe gripping segments downwardly in the socket and into gripping engagement with the drill pipe. 110

2. In well drilling apparatus, a rotary table, a tapered socket partaking of the rotary movement of the table, a sectional grip for rotating the drill pipe seating in said socket and having a gripping surface for 115 engagement with the pipe and adapted to impart the rotation of the table to the drill pipe, an overstanding sectional clamp for forcing the grip down in the socket, the sections of said clamp being connected with the sections of said grip for effecting a lifting of the grip upon movement of the clamp in the reverse direction, said sectional clamp consisting of substantially flat complementary plates closely overstanding the socket and having portions interlocking in overlapped relation and short screw bolts engaging said overlapped portions for adjustably securing the clamp. 125

3. In well drilling apparatus, a rotary 130

- table, a tapered socket partaking of the rotary movement of the table, a sectional grip for rotating the drill pipe seating in said socket and having a gripping surface 5 for engagement with the pipe and adapted to impart the rotation of the table to the drill pipe, an overstanding sectional clamp for forcing the grip down in the socket, said clamp being connected with the grip for 10 effecting a lifting of the grip upon movement of the clamp in the reverse direction, means associated with the clamp for lifting the same to free the grip from holding engagement with the drill pipe and relatively stationary wedge bolts interposed between the sections of the clamp for automatically separating the same in the lifting movement.
4. In well drilling apparatus, a rotary table, a tapered socket partaking of the rotary movement of the table, a grip for rotating the drill pipe seating in said socket and having a gripping surface for engagement with the pipe and adapted to impart the rotation of the table to the drill pipe, an 20 overstanding clamp for forcing the grip down in the socket, said clamp being connected with the grip for effecting a lifting of the grip upon movement of the clamp in the reverse direction, means associated with the clamp for lifting the same to free the grip from holding engagement with the drill pipe and means for automatically opening the grip in the course of such lifting movement.
5. In well drilling apparatus, a rotary table, a tapered socket partaking of the rotary movement of the table, a grip for rotating the drill pipe seating in said socket and having a gripping surface for engagement 30 with the pipe and adapted to impart the rotation of the table to the drill pipe, an overstanding clamp for forcing the grip down in the socket, said clamp being connected with the grip for effecting a lifting of the grip upon movement of the clamp in the reverse direction, means for lifting the grip in its socket and means for automatically opening the grip in the course of such lifting movement.
6. In well drilling apparatus, a rotary table, a tapered socket partaking of the rotary movement of the table, a grip for rotating the drill pipe seating in said socket and having a gripping surface for engagement 40 with the pipe and adapted to impart the rotation of the table to the drill pipe and an overstanding clamp for forcing the grip down in the socket, said clamp being connected with the grip for effecting a lifting of the grip upon movement of the clamp in the reverse direction, said clamp being of sectional separable construction and the grip consisting of complemental sections supported and carried by the separable sections of the clamp.

7. In well drilling apparatus, a rotary table, a tapered socket partaking of the rotary movement of the table, a grip for rotating the drill pipe seating in said socket and having a gripping surface for engagement with the pipe and adapted to impart the rotation of the table to the drill pipe, an overstanding clamp for forcing the grip down in the socket, said clamp being connected with the grip for effecting a lifting of the grip upon movement of the clamp in the reverse direction, said clamp being of sectional separable construction and the grip consisting of complemental sections supported and carried by the separable sections of the clamp and screw means for lifting the sections of the clamp.

8. In well drilling apparatus, a rotary table, a tapered socket partaking of the rotary movement of the table, a grip for rotating the drill pipe seating in said socket and having a gripping surface for engagement with the pipe and adapted to impart the rotation of the table to the drill pipe, an overstanding clamp for forcing the grip down in the socket, said clamp being connected with the grip for effecting a lifting of the grip upon movement of the clamp in the reverse direction, said clamp being of sectional separable construction and the grip consisting of complemental sections supported and carried by the separable sections of the clamp, screw means for lifting the sections of the clamp and means for wedging the clamp sections apart during such lifting action.

9. In well drilling apparatus, a rotary table, a tapered socket partaking of the rotary movement of the table, a grip for rotating the drill pipe seating in said socket and having a gripping surface for engagement with the pipe and adapted to impart the rotation of the table to the drill pipe, an overstanding clamp for forcing the grip down in the socket, said clamp being connected with the grip for effecting a lifting of the grip upon movement of the clamp in the reverse direction, said clamp being of sectional separable construction and the grip consisting of complemental sections supported and carried by the separable sections of the clamp, screw means for lifting the sections of the clamp and means operable on the lifting of the clamp sections to force said sections apart.

10. In well drilling apparatus, a sectional grip for imparting the rotation of the table to the drill pipe and a clamp for securing the grip in holding engagement with the drill pipe, said clamp comprising complementary clamp bars overstanding the sections of the grip and connected with the grip sections for supporting the same, said clamp bars having reversely offset overlapping end portions with reversely extending open slots

therein and screw bolts positioned in line with the registering open slots.

11. In well drilling apparatus, a drill pipe driving grip for imparting the rotation of the rotary table to the drill pipe, said grip comprising separable sections of segmental form, a sectional clamp consisting of separable clamp bars supportingly connected with the respective sections of the grip, said 5 clamp bars being independently engageable about and removable from opposite sides of the drill pipe and having interlocking overlapping portions at their ends and means operative on the overlapping end portions 10 of said clamp bars to secure the grip sections in driving engagement with the drill pipe.
12. In well drilling apparatus, complementary clamp bars for engagement about the drill pipe, said clamp bars having overlapping end portions, drill pipe grips dependent from said bars and screw means operative on said overlapping portions of said clamp bars to secure the grips in rotary driving engagement with the drill pipe.
13. In well drilling apparatus, complementary clamp bars for engagement about the drill pipe, drill pipe grips dependent from said bars and screw means operative on said clamp bars to secure the grips in rotary driving engagement with the drill pipe, said screw means having connection with the clamp bars for effecting the release of the grips from the drill pipe upon reverse action of the same and means for automatically wedging the clamp bars apart in such reverse action of the screw means.

14. In well drilling apparatus, a sectional clamp having overlapping end portions, a sectional pipe driving grip carried by and 40 actuated by said clamp and screw means engaging both above and below the overlapping portions of the clamp sections for shifting the sectional clamp in opposite directions for forcing the grip into holding engagement with the drill pipe and for releasing the same from holding engagement therewith.

15. In well drilling apparatus, a sectional clamp, a sectional pipe driving grip carried 50 by and actuated by said clamp, screw means for shifting the sectional clamp in opposite directions for forcing the grip into holding engagement with the drill pipe and for releasing the same from holding engagement therewith and means for automatically separating the grip sections in the course of such releasing movement of the clamp.

16. In well drilling apparatus, complementary clamp bars, a drill pipe rotating 60 grip actuated thereby and relatively stationary wedge means for forcing the clamp bars

apart in the adjustment of the same in one direction.

17. In well drilling apparatus, the combination with a rotary table and tapered socket 65 partaking of the rotary movement of the table, of a sectional clamp overstanding said socket and comprising separable clamp plates independently engageable about the sides of the drill pipe extending down 70 through the table, drill pipe gripping segments dependent from the sections of said overstanding clamp, said clamp sections having a bearing on the heads of said segments and means for forcing the sections of the 75 clamps downwardly with respect to the table to thereby force the pipe gripping segments downwardly in the socket and into gripping engagement with the drill pipe, the tapered socket for the pipe gripping segments being 80 carried by a sleeve which is slidingly keyed in the table so that it may be raised and lowered therein and the pipe gripping segments having elongated gripping faces to hold the pipe in the lifting and lowering action of 85 said sleeve as well as in the rotary movement of the table.

18. In well drilling apparatus, the combination with a rotary table and a tapered socket 90 partaking of the rotary movement of the table, of a two-part clamp overstanding said socket and comprising complementary flat clamp plates recessed in their opposing edges to freely receive between them a drill pipe extending down through the socket and 95 a plurality of drill pipe gripping segments loosely dependent from each of the clamp plates with freedom of motion in all directions sufficient to permit each to adjust itself individually into gripping engagement with 100 the pipe.

19. In well drilling apparatus, a rotary table, a tapered socket partaking of the rotary movement of the table, a grip for rotating the drill pipe seated in said socket 105 and having a gripping surface for engagement with the pipe and adapted to impart the rotation of the table to the drill pipe, an overstanding clamp for forcing the grip down in the socket, said clamp being connected with the grip for effecting a lifting of the grip upon relative vertical movement of the clamp and socket, means for effecting relative vertical movement of the clamp and socket to free the grip from holding engagement with the drill pipe and means for automatically opening the grip in the course of such relative movement.

In witness whereof, I have hereunto set my hand this 30th day of January, 1926.

WALDO SHELDON.
